A. B. SMITH

VOICE CURRENT TELEPHONE REPEATER

Original Filed Mar. 5, 1919

—Inventor—

Arthur Bessey Smith

W. Hales Atty.

UNITED STATES PATENT OFFICE.

ARTHUR BESSEY SMITH, OF EVANSTON, ILLINOIS, ASSIGNOR TO AUTOMATIC ELECTRIC COMPANY, OF CHICAGO, ILLINOIS, A CORPORATION OF ILLINOIS.

VOICE-CURRENT TELEPHONE REPEATER.

Application filed March 5, 1919, Serial No. 280,695. Renewed June 12, 1922. Serial No. 567,744.

To all whom it may concern:

Be it known that I, ARTHUR BESSEY SMITH, a citizen of the United States of America, and a resident of Evanston, in the county of 5 Cook and State of Illinois, have invented certain new and useful Improvements in Voice-Current Telephone Repeaters, of which the following is a specification.

My invention relates in general to a voice 10 current repeater for use in a telephone system and relates more specifically to an improved method of switching a voice current amplifier from connection in a trunk line to repeat in one direction to connections 15 which adapt it to repeat voice currents in the opposite direction.

The object of my invention is to provide a simple and efficient device of this character 20 in which the repeater is left connected for repeating in the direction in which it was last used; that is, a person may continue talking from one end of a trunk line as long as may be desired, and will switch the repeater once at the beginning of his conversation, if it was previously used in the opposite 25 direction, and will not have to perform any more switching operations until after the party at the opposite end has spoken to reverse the repeater. In this way only the 30 first part of the first word spoken is used to do the work of reversing and should there be a pause in the conversation he may continue after the pause without having to again reverse the connection.

35 I will point out the features and objects of my invention more in detail by referring to the accompanying drawing, in which I have shown only a portion of a trunk line, one end of which I will call the "west" end and the other the "east" end. It will be understood that this trunk line may be connected 40 up for use in any desired type of automatic or manual system.

Interposed in the center of this trunk 45 line I have shown a voice current repeater consisting of a device, shown as a receiver 2 for simplicity, for receiving voice currents and for repeating the same into a transmitter 3 in series with an induction 50 coil primary 4 which induces corresponding currents in the secondary 5. It is to be understood that this transmitter and receiver arrangement may be any known type of voice current amplifier. The relay 6 is provided for switching either the receiver or

the secondary of the induction coil in series with either end of the trunk line; that is, when the magnet is deenergized (as shown) voice currents coming from the west end will be amplified and repeated to the east end, 60 while when relay 6 is energized, voice currents will be amplified and repeated from the east end to the west end.

Assuming that the last party to send voice 65 current over the line was the one at the west end, then the device will be left in the position shown. Now, if the party at the west end starts to talk again, voice current will travel from the conductor 14, through springs 15 and 16, receiver 2, springs 17 and 18, and back over conductor 19, thus agitating 70 the receiver 2 and causing the transmitter 3 to in turn be agitated to induce an amplified voice current in winding 5 of the induction coil. This induced current will 75 follow a path as follows: from conductor 20, through springs 21 and 22, winding 5 and sensitive relay 7 in multiple, sensitive relay 8, springs 23 and 24, and back over conductor 25 to the instrument of the party on the east 80 end. The relays 7, 8 and 9 are all of a sensitive type of relay which respond to alternating current in such a manner that their weighted armatures fly off to keep the contact between the two springs open for a 85 larger part of the time. These relays may be of the type shown in U. S. Letters Patent No. 1,221,299, granted April 3, 1917, to John Erickson. Now it will be seen that relays 7 and 8 are included in the circuit of the 90 amplified voice current so that both of said relays will be energized during conversation from the west end. The relays 10 and 11 are differential relays. Relay 12 is slightly 95 slow in operation. Now when relays 7 and 8 are energized as described then both winding of relays 10 and 11 will be open or closed simultaneously at springs 26, thus preventing any movement of said relays. Relay 12 remains energized during this time from 100 ground through back contacts of relays 6 and 11. Now should the subscriber at the west end cease conversation and the subscriber at the east end commence to talk, then the relay 8 alone will energize in the east 105 branch circuit, as in this case weak talking current only is flowing through the last traced circuit of the east end of the trunk. The sensitive relay 7 is in series with a resistance 27 and is adjusted so that it will not 110

2
energize with weak current but only with amplified current. Now when relay 8 operates it will be seen that the circuit of the upper winding of relays 10 and 11 is opened 5 and said relays immediately energize through their lower windings. The circuit of the lower windings extends from battery through said windings, springs 28, springs 29 and 30, springs 26, springs 31 and 32, and 10 springs 33 and 34 to ground. Relay 10 pulls up and immediately closes the circuit of switching relay 6 at springs 35. Relay 6 starts to pull up its armatures to switch the 15 connections to the amplifier and also switches the ground connection from spring 33 to spring 36. The springs 34 and 33 stay in contact until springs 34 and 36 close. Relay 11 pulls up before relay 6 completes its stroke so that the circuit of relay 12 is held 20 closed through springs 37 and 38. As soon as relay 6 completes its stroke and opens springs 33 and 34, then the circuit for the lower winding of relays 10 and 11 is broken. The circuit of relays 10 and 11 was broken at 25 springs 30 and 39 when relay 11 was energized, but a new locking circuit was closed at springs 40 which is the circuit that is now broken at springs 33 and 34. Relay 10 is a differentially wound polarized relay and the 30 armature is arranged to stay where it is put; that is, if the lower winding alone is energized the armature closes springs 35 which stay closed as long as both windings are 35 energized together or as long as the lower winding alone is energized, but opens the springs 35 if the upper winding alone is energized. This type of relay is well known in telegraph work and may have two separate coils if desired. Now when the circuit 40 of the two lower windings are opened springs 35 stay closed but relay 11 falls back. The circuit of relay 12 is now opened at springs 37 and 38, the springs 29, 30 and 39 close again to render the relays 10 and 11 45 again subject to the control of relays 7 and 9 and springs 40 again open.

Now as soon as relay 6 energizes, a new path is closed for the voice currents from the east end of the trunk extending from conductor 20, springs 21 and 41, receiver 2, springs 42 and 24, and conductor 25. The amplified current now flows through from conductor 14, springs 15 and 43, secondary 5 and relay 7 in multiple, relay 9, and springs 55 44 and 18 to conductor 19. Relays 7 and 9 energize at this time simultaneously, relay 7 rendering relay 9 ineffective to produce any change in the circuits of relays 10 and 11, by opening both sides of said coils.

Now should the east party cease and the west again start then the operations are somewhat similar, the switching being done by relay 9 in this case, while relay 7 is quiet. Relay 9 opens the circuit of the lower windings of relays 10 and 11 at springs 28. The

relay 10 operates to open the springs 35 in the circuit of relay 6. The deenergization of the relay 6 causes relay 12 to be energized as soon as relay 11 is deenergized, the latter operation following as a result of the opening 70 of the circuit for both of its windings at springs 34 and 36 by relay 6.

It will thus be seen that as long as relay 7 is operating, neither of the relays 8 or 9 can be effective to switch the amplifier but if 75 either relay 8 or 9 is operated alone then the amplifier is switched over and the circuit so changed that relay 7 prevents any further change and that the other sensitive relay is prepared to do the next switching 80 over.

It will be understood that only the first wave of weak talking current is used to start the switching and that immediately the relay 7 becomes effective to respond to 85 amplified currents to hold the device stationary.

Having described the features and aspects of my invention what I consider to be new and desire to have protected by Letters 90 Patent will be pointed out in the appended claims.

What I claim as my invention is:

1. In a telephone system, a line, an amplifier associated with said line for repeating voice currents from either end thereof to the other, said repeater always normally connected to amplify and repeat in one direction a switching device for changing the connections of said amplifier to adapt it for repeating from the other end thereof, a controlling device for each end of said trunk line for operating said switching device, and another controlling device for rendering both of said first controlling devices ineffective. 100

2. In a telephone system, a line, an amplifier associated with the line, a relay for reversing the connection of said amplifier with the line for repeating voice currents in either direction thereover, means for controlling said relay consisting of a device for each end of the trunk line and each controllable over its respective end to either energize or deenergize said relay, and another device 115 controllable over either end of the line to prevent the control of said relay by either of said devices. 110

3. In a telephone system, a line, an amplifier normally connected to the line for repeating voice currents from one end to the other thereof, means for reversing said amplifier to repeat in the opposite direction, a sensitive device for each end of the line responsive to voice currents thereover for 120 controlling said means, one of said devices normally inoperative, means for rendering the other device ineffective when voice currents are sent from one end of the line and means controlled thereby for operating said 125 130

first means to reverse the amplifier when currents are sent from the other end of the trunk line and to render the other device operative.

5 4. In a telephone system, a line, an amplifier normally connected to the line for repeating voice currents from one end to the other thereof, means for reversing said amplifier to repeat in the opposite direction, a 10 sensitive device for each end of the line responsive to voice currents thereover for controlling said means, one of said devices normally inoperative, means for rendering the other device ineffective when voice currents are sent from one end of the line and means controlled thereby for operating said first means to reverse the amplifier when currents are sent from the other end of the trunk line and to render the other device 15 operative, and means controlled from both ends of the line for rendering all of said devices ineffective.

5. In a telephone system, a pair of lines joined by voice current repeater, said repeater always normally connected to amplify and repeat from one line to the other, a sensitive relay in each line operated by voice currents passing over its associated line to switch the repeater to repeat from its line 20 to the other and another sensitive relay controlled by the amplified voice currents to render both of said first sensitive relays ineffective.

6. In a telephone system, a pair of lines 35 joined by a voice current repeater, a sensitive relay for each line, each relay having means for reversing the connection of the repeater to repeat from its associated line, each relay responsive to initial voice currents over its line to perform said switching operation, and another sensitive relay operated by the voice current over said line to cut off first mentioned relay from said line and to render the other of said relays ineffective.

45 7. In a telephone system, a pair of lines joined by a voice current repeater, a relay for switching the connections of said repeater to said lines to repeat voice currents from either line, a sensitive relay for one line 50 for controlling said switching relay in one manner and a sensitive relay for the other line for controlling the said first relay in another manner, and another sensitive relay operated from either line for rendering both 55 of said other sensitive relays ineffective.

8. In a telephone system, a pair of lines joined by a voice current repeater normally connected to repeat voice currents from one line to the other, a switching relay adapted to 60 either remain energized or deenergized to connect the repeater for repeating from either line, a controlling device for one line for energizing said relay and a controlling device for the other line for deenergizing 65 said relay, and a common controlling device

operated from either line to prevent any change in the energization or deenergization of said relay while voice currents are being repeated from either line to the other.

9. In a telephone system, a pair of lines 70 joined by a voice current repeater, said repeater always normally connected to amplify and repeat from one line to the other, a sensitive relay for each line operated by voice currents, a polarized relay in said repeater, 75 one of said sensitive relays adapted to energize said polarized relay and means responsive upon the energization of said polarized relay for switching the said repeater to amplify and repeat in the opposite direction, 80 another sensitive relay in said repeater adapted to be controlled from either line, and means responsive to the energization of said relay for rendering either one or the other of said first mentioned sensitive relays 85 inoperative depending upon which direction said repeater is repeating voice currents.

10. In a telephone system, a pair of lines 90 joined by a voice current repeater always normally connected to amplify and repeat in one direction, a sensitive relay associated with each line and controlled by voice currents thereover, a polarized relay in said repeater, one of said sensitive relays adapted to energize said polarized relay, means responsive upon the energization of said polarized relay for switching the repeater to repeat and amplify in the opposite direction and for rendering the said last mentioned sensitive relay inoperative to voice currents 95 from its associated line.

11. In a telephone system, a pair of lines 100 joined to a voice current repeater always normally connected to repeat and amplify in one direction, a relay adapted to switch the connection of said repeater to repeat and amplify in the opposite direction, a pair of double wound relays for controlling the operation of said relay, a normally closed circuit for both windings of each of said controlling relays, a sensitive relay for opening the circuit of one winding of each controlling relay to operate said switching relay, and a second sensitive relay adapted to open the second winding of each controlling 110 relay to deenergize said switching relay.

12. In a telephone system, a pair of lines 115 joined to a voice current repeater always normally connected to repeat and amplify in one direction, a relay adapted to switch the connection of said repeater to repeat and amplify in the opposite direction, a pair of double wound relays for controlling the operation of said relay, a normally closed circuit for both windings of each of said controlling relays, a sensitive relay for opening the circuit of one winding of each controlling relay to operate said switching relay, and a second sensitive relay adapted to open the second winding of each controlling 120 125 130 relay to deenergize said switching relay.

- lay to deenergize said switching relay, and a third sensitive relay adapted to open the circuit of both windings of said controlling relays.
- 5 13. In a telephone system, a pair of lines joined to a voice current repeater always normally connected to repeat and amplify in one direction, a relay adapted to switch the connection of said repeater to repeat and 10 amplify in the opposite direction, a pair of double wound relays for controlling the operation of said relay, a normally closed circuit for both windings of each of said controlling relays, a sensitive relay for opening 15 the circuit of one winding of each controlling relay to operate said switching relay, and a second sensitive relay adapted to open the second winding of each controlling relay to deenergize said switching relay, and the 20 circuit of both windings of each of said controlling relays adapted to be opened and closed by the operation of said switching relay.
14. In a telephone system, a pair of lines 25 joined to a voice current repeater always normally connected to repeat and amplify in one direction, a relay adapted to switch the connection of said repeater to repeat and amplify in the opposite direction, a pair of 30 double wound relays for controlling the operation of said relay, a normally closed circuit for both windings of each of said controlling relays, a sensitive relay for opening 35 the circuit of one winding of each controlling relay to operate said switching relay, and a second sensitive relay adapted to open the second winding of each controlling relay to deenergize said switching relay, and a 40 normally energized relay for controlling the circuit of one winding of each of said controlling relays.
15. In a telephone system, a pair of lines joined by a voice current repeater, said re- 45 peater always normally connected to repeat and amplify from one line to the other, a 50 switching relay for changing the circuits of said repeater to amplify and repeat in the opposite direction, a differential relay for controlling said switching relay, a sensitive device responsive to voice currents from either of said lines, and circuits for said differential relay controlled by said sensitive device.
16. In a telephone system, a pair of lines joined by a voice current repeater, said repeater always normally connected to repeat and amplify from one line to the other, a 55 switching relay for reversing said repeater, to repeat and amplify in the opposite direction, a differential relay for controlling said 60 switching relay, a sensitive device for each line responsive to voice currents thereover, and a circuit for each winding of said differential relay, each circuit including normally closed contacts on each of said sensitive devices.
17. In a telephone system, a pair of lines joined by a voice current repeater, said repeater always normally connected to repeat and amplify from one line to the other, a 70 switching relay for reversing said repeater to repeat and amplify in the opposite direction, a differential relay for controlling said 75 switching relay, a sensitive device for each line responsive to voice currents thereover, a circuit for each winding of said differential relay, each circuit including normally closed contacts on each of said sensitive devices, and a third sensitive device responsive to voice currents from either line to render the operation of the first mentioned sensitive devices ineffective to control said differential relay.

Signed at Chicago, Cook County, Illinois,
this 27th day of February, 1919.

ARTHUR BESSEY SMITH.
